CLAIM

The ornamental design for an archery bow string stop, as shown and described.

DESCRIPTION

FIG. 1 is a top perspective view of an archery bow string stop, showing my new design;

FIG. 2 is a right side elevation view thereof;

FIG. 3 is a left side elevation view thereof;

FIG. 4 is a front side elevation view thereof;

FIG. 5 is a rear side elevation view thereof;

FIG. 6 is a top plan view thereof; and,

FIG. 7 is a bottom plan view thereof.

The broken line in the drawings depicts unclaimed portion of the archery bow string stop only and forms no part of the claimed design.
